UNITED STATES PATENT OFFICE.

ALFRED T. STURT, OF NEW YORK, N. Y., ASSIGNOR TO GENERAL MOTORS CORPORATION, OF DETROIT, MICHIGAN, A CORPORATION OF DELAWARE.

DESIGN FOR A MOTOR-DRIVEN FARM-TRUCK.

59,790.

Specification for Design.

Patented Nov. 22, 1921.

Application filed March 13, 1920. Serial No. 365,667. Term of patent 14 years.

To all whom it may concern:

Be it known that I, ALFRED T. STURT, a citizen of the United States, residing at New York, in the county of New York and State of New York, have invented a new, original, and ornamental Design for Motor-Driven Farm-Trucks, of which the following is a specification, reference being had to the accompanying drawing, forming part thereof.

Figure 1 is a view showing my improved motor driven farm truck in side elevation. Fig. 2 is a view showing the same in plan.

I claim:

The ornamental design for a motor driven farm truck as shown.

ALFRED T. STURT.
